UNITED STATES PATENT OFFICE

WILLIAM MARCROFT, OF CRANSTON, AND GEORGE N. TAYLOR, OF EAST PROVIDENCE, RHODE ISLAND, ASSIGNEES TO UNIVERSAL WINDING COMPANY, OF BOSTON, MASSACHUSETTS, A CORPORATION OF MASSACHUSETTS

YARN CLEANER AND SLUB DETECTOR

Application filed October 11, 1927. Serial No. 225,549.

This invention relates to improvements in yarn-cleaners and slub-detectors for cleaning lint, fluff, specks, motes and other foreign matter from yarn, thread or other filaments and for detecting slubs and enlargements thereon. My improved yarn-cleaner and slub-detector is adapted for use with winding machines and other textile apparatus to operate on the yarn, thread or other strand as it feeds thereto in the various processes of conversion.

A principal object of the invention is to provide a yarn-cleaner and slub-detector of the type specified for scraping lint and other adhering matter from the yarn while also acting to detect the presence of a slub, bunch or enlargement on the strand so that it may be removed before it passes into the product.

Another object of the invention is to provide a device of the type specified which is adapted to cooperate with the stopping-mechanism of the machine to arrest the operation thereof by the detection of the slub or bunch without breaking the strand feeding to the machine.

Another object of the invention is to provide a device of the type specified which is adapted to clean the yarn on all sides and to detect slubs or enlargements which have been flattened lengthwise of the strand.

Another object of the invention is to provide a device of the type specified which may be adjusted with accuracy and precision in accordance with the size or thickness of the yarn to be operated upon.

Another object of the invention is to provide a device of the type specified of simple construction with its parts constructed of sheet-metal stampings to render it economical to manufacture.

Another object of the invention is to provide a device of the type specified which is proof against derangement or getting out of order and durable in use over long periods.

Further objects of the improvement are set forth in the following specification which describes a preferred embodiment of the invention as illustrated by the accompanying drawings. In the drawings:

Fig. 1 is a view of a well-known type of

winding machine showing the present improved yarn-cleaner and slub-detector as applied to use therewith;

Fig. 2 is an enlarged perspective view of the improved yarn-cleaner and slub-detector;

Fig. 3 is a side elevation of the same showing its support or standard partly in section;

Fig. 4 is a plan view of the device;

Fig. 5 is a further enlarged plan view of the operating end of the device illustrating the means for adjusting the cooperative relation of the yarn-cleaning and slub-detecting members; and

Fig. 6 is an enlarged detailed view of the adjusting-means.

Fig. 1 of the drawings illustrates a well-known type of winding machine for winding yarn, thread and other filaments or fibers into cops or packages. While it is preferred to herein illustrate the improved yarn-cleaner and slub-detector in connection with a winding machine of this type it is to be understood that the device may be used with other forms of apparatus as employed in the various processes of converting, treating and transferring textile materials. It is also to be understood that the present invention is herein shown and described in a preferred form of construction by way of example only, it being susceptible of variations as required to adapt it to other types of machines or other methods of use.

In Fig. 1, 2 designates the frame of the winding machine which supports bearings for a rotatable winding-spindle or mandrel 3 on which the cop, cone or bobbin is wound. The yarn, thread or other strand material is traversed longitudinally of the winding-spindle 3 by means of a reciprocating thread-guide 5 to deposit it in coils on the cop-tube or holder C. The thread-guide 5 is carried on a traverse-frame 6 which is mounted to swing on a pivot 7, whereby to allow the guide to move away from the axis of the winding-spindle 3 as the cop or package is built up thereon.

The winding mechanism is operated from power-driven means, such as a belt-pulley and clutch, not herein illustrated, and its operation is controlled from a starting-lever or

handle 10. The starting-lever 10 is rocked into the position shown in Fig. 1 to shift the clutch to start the operation of the machine, and is maintained in this position to continue the winding operation through suitable detent-means as next described. The starting-lever 10 carries a depending sickle-shaped arm 11 provided at its end with a detent-latch 12 adapted to be engaged with a lock or shoulder 13 formed on an arm 14 projecting upwardly from a curved lever or quadrant 15. The quadrant 15 is pivoted to the side of the frame 2 at 16 and is normally held by gravity to maintain its detent-shoulder 13 in engagement with the detent-latch 12 on the arm 11 of the lever 10. The above-described arrangement of the essential elements of the starting- and stopping-mechanism of the machine are of well-known construction and it will be understood that when the outer end of the lever or quadrant 15 is lifted the detents will be released to effect the action of the stopping-mechanism to arrest the operation of the machine.

The outer end of the quadrant 15 carries a stop-lever or drop-wire 17 pivoted on a screw 18 and having a depending arm 19 terminating in a horizontal cross-bar 20 which is normally supported from the strand of yarn *y* to maintain the stop-lever in suspension as illustrated in Fig. 1. The stop-lever 17, preferably formed of wire, is of a bell-crank type having a second arm 21 extending at substantially right-angles to the arm 19 and connected thereto by a cross-strut or tie 22. The lower end of the arm 21 is adapted to make contact with the serrated or toothed periphery of a wheel 23 which is continuously rotated during the operation of the winding machine. The wheel 23 is carried on the end of the rotating shaft 7 which forms the pivot for the swinging traverse-frame 6. The shaft 7 turns in the direction indicated by the arrow in Fig. 1 and drives the traverse-cam, not herein shown, which reciprocates the thread-guide 5 by means of the usual connections. It will be understood that when the bar 20 on the stop-lever 17 is released from the strand *y*, due to its breakage or the exhaustion of the supply, the lever will rock under the action of gravity to cause its arm 21 to engage with the toothed periphery of the wheel 23. The rotation of the wheel 23 will thereupon act on the stop-lever 17 to pry the outer end of the quadrant 15 upwardly whereby to release the detents to effect arrest of the winding machine in the manner as well known to those versed in the art. The stop-lever 17 is formed with another elbow-shaped arm 24 by which it may be connected for operation from the slab-detector of the present invention, these connections being as later described.

As the yarn, thread or other strand material feeds to the winding-spindle, tension is

applied thereto to resist its draft in accordance with the usual practice, any suitable form of tension-device being employed for this purpose. Fig. 1 of the drawings illustrates a so-called finger-tension comprising two opposite plates or grids 25 formed with alternating bars 26 across which the strand *y* draws. The tension-plates or grids 25 are hinged on a rod 27 supported from a forked bracket 28 having an arm attached to the frame 2 at 29. Suitable means, such as illustrated in general at 30, are employed for swinging one tension-grid 25 toward the other to adapt their bars 26 to press against the strand *y* to cause it to follow a tortuous or sinuous course thereover whereby to apply resistance to its draft. On the top of the bracket 28 is fastened a plate 33 having its forward edge disposed in position to cause the strand *y* to draw thereacross as it travels between the tension-grids 25. A loop-like arm or hook 34 reaches up across the bar 20 on the stop-lever 17 to limit the swinging movement of the latter as the strand *y* draws thereunder. From the bar 20 the strand *y* leads up over a guide-pulley 35, thence down around a guide-rod 36, and drawing across the thread-ball 37 on the traverse-frame 6, feeds through the thread-guide 5 to be deposited thereby on the cop or bobbin being wound.

The improved yarn-cleaner and slab-detector forming the subject-matter of the present invention may be applied to the winding machine in any desired position, and conveniently it is attached to the top of the tension-bracket 28 to adapt it to act on the yarn or thread after the latter has drawn through the tension-device. For attaching and supporting the device on the bracket 28 a mounting or standard 40 of sheet-metal is provided having a flat rest or foot 41 formed with a slot 42, see Figs. 2 and 3. The foot 41 rests against the top of the plate 33 and is secured in place by the screw or bolt 43 used to fasten the plate to the bracket 28. The pivot rod 27 for the tension-grids 25 projects up through the slot 42 in the foot 41 and serves as a dowel to hold the support from turning on the screw 43.

The mounting or standard 40 comprises a vertical arm 44 extending upwardly from the foot 41 and bent over at the top to form a horizontal ledge or shelf 45. At either side of the shelf 45 are vertical ears 46 and 47 which form the pivotal supports for the operating mechanism of the yarn-cleaner and slab-detector. The rearward ear 47 of the standard 40, as viewed in Figs. 2 and 3, is extended to the right in a horizontal arm 48 having its end portion 49 bent or folded back at an angle of forty-five degrees, as shown most clearly in Figs. 4 and 5. This angular branch of the arm 48 forms the support for an adjustable yarn-rest or bearing-member 50 which cooperates with the movable slab-

detector element 65, to be later described, to clean the yarn and to detect the presence of slubs and enlargements thereon. The bearing-member 50 comprises an arm 51 adapted to overlie the side of the angular branch 49 of the arm 48 and provided with bent-over flanges 52 overlapping the edges thereof to form a sliding support thereon, see Figs. 3 and 5. Journalled in a hole 53 in the branch 49 is a stud 54 formed with an eccentric body-portion 55 projecting through a vertical slot 56 in the supporting arm 51 of the member 50, see Fig. 6. The stud 54 has a head 57 formed with a hexagonal socket 58 and its opposite end is riveted over to form a flange 59 abutting the side of a dished spring-washer 60 which bears against the rearward side of the branch 49. Through this construction the member 50 is held frictionally against the face of the branch arm 49, and by turning the stud 54 with a suitable wrench the member may be slid longitudinally of the arm to adjust its yarn-rests in cooperative relation with respect to the slab-detector in the manner as later explained.

The bearing-member or yarn-rest 50 is bent around at 61 to form a horizontal arm 62 which extends at right-angles to the arm 48 on the standard or mounting 40. The arm 62 is split or sheared longitudinally to form a narrower strip 63 which is bent outwardly at an angle and then folded back in a part 64 which extends across and at right-angles to the main arm. Through this construction the arm 62 provides a rest or bearing for the strand y disposed in one vertical plane while the auxiliary arm 64, extending thereacross, forms a bearing for the strand in a plane at right-angles to the main rest. These two yarn-rests 62 and 64 cooperate with two opposite strand-engaging edges of the detector-member 65 in the manner as next explained.

The detector-element 65, which normally cooperates with the faces of the yarn-rests 62 and 64 to scrape lint and other accumulations from the strand material and to also detect the presence of a slab or enlargement thereon, consists essentially of a flat plate having ears 66, see Figs. 2, 3 and 4, bent down from one end thereof. The detector 65 is pivoted on the mounting 40 by means of a cross-pin 67 extending through its ears 66 and riveted through the ears 46 and 47 on the standard 40. When the detector-element or plate 65 is in horizontal position, as shown in Figs. 2 and 3, its outer end clears the face of the yarn-rest 62 to provide a space therebetween through which the strand y draws. At this end of the plate 65 is an integral strip 68 bent upwardly from its side and then folded over again in a smaller, flat plate 70 overlying the main plate in parallel spaced relation with respect thereto. The upper supplemental plate 70 has its lateral edge 71 extending parallel with and spaced away

from the side of the yarn-rest 64 a distance equal to the space between the end of the main plate 65 and the rest 62. It will thus be seen that the strand y drawing up between the outer edge of the plate 65 and the face of the rest 62 may be made to follow a course between the lateral edge of the plate 70 and the face of the rest 64. The purpose of this arrangement is to provide that the yarn shall be acted upon on all four sides as it draws between the detector-element and the fixed rests or bearing-faces whereby to more completely scrape and clean the yarn to remove all matter adhering thereto.

It will now be understood why the adjusting-means for the member 50 is arranged at an angle to the arm 48. It has been explained that the member 50 is slideable on the branch 49 of the arm 48 in a plane disposed at an angle of forty-five degrees to said arm, and it will be seen therefore that when the member 50 is moved in either direction in this plane it will concurrently adjust the yarn-rest 62 and the rest 64 respectively with the outer edge of the plate 65 and the lateral edge 70 of the plate 70. In other words, the setting of the member 50 effects a two-fold adjustment of its yarn-rests 62 and 64 with respect to the cooperating right-angled edges of the yarn-cleaning and slab-detecting element 65.

At the pivoted end of the plate 65 is a trigger-arm 72 bent downwardly at substantially right-angles to the plane of the plate. The lower edge of the arm 72 is adapted to engage over the upper edge of a pivoted trip-lever 75 which is weighted at its opposite end. The trip-lever 75 is provided with ears 76 by means of which it is pivoted on a cross-pin 77 extending between the ears 46 and 47 on the standard 40. Extending rearwardly from its pivot are two arms 78 formed by narrower strips of the sheet-metal stock twisted at right-angles to the plane of the main portion of the lever. A tubular-rod or pin 79 extends between the arms 78 and carries a cylindrical weight 80 for counter-balancing the lever 75 to cause it to drop into the position illustrated by the dotted lines in Fig. 3 when the trigger-arm 72 is released from its edge.

Hooked through the tubular-rivet 79 is a wire rod 81, shown in Fig. 2, which is bent at right-angles to reach up to the drop-wire or stop-lever 17, see Fig. 1, to adapt it for connection therewith. The upper end of the rod 81 is bent into a loop 82 through which is hooked the end of the elbow-shaped arm 24 on the stop-lever 17. This looped connection permits the stop-lever 17 to move independently of the trip-lever when released by the breakage or exhaustion of the yarn drawing across its bar 20, and also adapts the trip-lever 75 to move the stop-lever into engagement with the toothed wheel 23 when the trip-lever is released from the trigger 72 on the slab-detector 65. The method of operation of the complete de-

vice as applied to use with the winding machine herein illustrated is as follows:

In preparing the winding machine for operation the strand y of yarn, thread or other material is led between the tension-plates 25; across the bail or bar 20 on the stop-lever 17; and thence entered into the yarn-cleaner by drawing it up across the side of the yarn-rest 62 and directing it in back of the edge 71 of the plate 70 on the slab-detector 65 to cause it to lead across the face of the auxiliary yarn-rest 64. Thence the strand y passes up over the guide-pulley 35, down around the guide-rod 36, and to the thread-guide 5 in the manner as before explained. In Fig. 1 the winding machine is represented as having a conical tube C applied to the winding-spindle 3 and the end of the yarn is suitably attached to this tube or cop-holder in the usual manner. To start the winding the traverse-frame 6 is swung into position to bring the thread-guide 5 against the surface of the cone-holder or tube C, and the starting-lever or handle 10 is then rocked to the position shown in Fig. 1 to engage its latch 12 with the detent-shoulder 13 on the quadrant 15. This manual operation effects the clutching of the winding-spindle with its driving-means in the usual manner whereby to cause the spindle to be rotated and the thread-guide 5 to be reciprocated along the face of the cone-tube or holder C. As the yarn is wound onto the cone-tube or holder C the tension of the strand y drawing across the bar 20 of the stop-lever 17 maintains the latter suspended with its arm 21 free from contact with the stopping-wheel 23, so that normally the machine continues to wind as long as it is supplied with yarn feeding thereto.

As the strand y draws upwardly between the outer edge of the slab-detector 65 and the face of the yarn rest 62 and also between the lateral edge 71 of the plate 70 and the face of the auxiliary rest 64 it is scraped on four sides to remove any lint, fluff, specks or motes adhering thereto. It will thus be observed that any foreign substance such as lint, specks or motes which may have collected on the yarn and flattened thereagainst cannot escape the scraping surfaces on the four sides of the strand, the device being thereby much more efficient and reliable for removing all accumulations from the yarn.

When a slab or bunch appears on the yarn it will pass first across the rest 62 and either engage the edge of the detector-element 65 or, failing in this, will pass on to the rest 64 and engage the edge of the upper plate 70. That is to say, should the slab or enlargement pass into the device in such position as to be flattened against the yarn-rest 62 so that it may escape engagement with the outer edge of the detector-element 65 it will pass on to the yarn-rest 64 in such manner as to invariably cause it to engage with the lateral edge 71 of the

plate 70. Therefore, whenever a slab or enlargement engages with either detecting edge of the element 65 it will act on said detector to swing the latter upwardly to permit the obstruction to pass thereby. As the detector 65 is swung upwardly in this manner its trigger-arm 72 will be released from the edge of the trip-lever 75, thereby permitting the weighted end of the lever to drop. The dropping of the trip-lever 75 acts through the rod or link 81 to rock the stop-lever 17 into engagement with the periphery of the stopping-wheel 23. The stopping-lever 17 is thus caused to lift the quadrant 15 to disengage the detents 12 and 13 whereby to release the starting-lever 10 to cause the stopping-mechanism to arrest the operation of the whole machine.

The stopping of the machine is practically instantaneous so that the slab, bunch or other enlargement can not pass through the thread-guide into the winding, but may be readily discovered in the length of yarn extending between the slab-catcher and the guide. The operator is thus enabled to examine the length of yarn containing the slab or enlargement and if necessary to break out a section thereof and piece up the material to remove the imperfection. After the operation of the machine has been arrested in the manner as above described the slab-detector is set for further operation by simply lifting the trip-lever 75 and engaging it with the trigger-arm 72.

It will be observed from the foregoing that the invention provides a particularly simple and efficient device for cleaning yarn, thread and other textile materials to remove lint, fluff and adhering matter therefrom, while also detecting the presence of slubs and bunches which cannot be scraped off from the strand. Upon the detection of a slab, bunch or other enlargement on the yarn the device acts automatically to arrest the operation of the machine without breaking the strand. This improved method of operation provides against unnecessary breaking out and waste of material when the obstruction in the yarn can be removed or reduced manually and thereby effects a saving which is particularly important when silk or other expensive material is being operated upon. It also reduces the number of splices and knots in the yarn and thereby improves the quality of the ultimate product for which the material is intended.

It has been explained that the width of the slits or openings through which the strand passes may be adjusted by setting the yarn-rest element 50, this adjustment having a two-fold effect and insuring that the spaces between the cooperative yarn-cleaning element shall always be uniform and properly proportioned to the size of the yarn being operated upon. Moreover, since the direction of adjustment is at an angle of forty-five degrees to each adjusted face the present in-

genious arrangement makes for a more minute and accurate setting of the parts, in effect, a vernier adjustment.

The parts of the improved device may be constructed of sheet-metal to render them economical to manufacture and the utter simplicity of the operating-mechanism not only reduces the cost of manufacture, but tends to render it more efficient and reliable in use and less liable to derangement or getting out of order. The arrangement of the detector-member whereby it holds the trip-lever through the means of its trigger-arm results in very little pressure being imposed on the detector to resist its movement under the action of the slub on the yarn, and thus the device is rendered extremely sensitive and quick of action in its control of the stopping-mechanism of the machine to which it is applied.

As a further improvement, it is noted that the device may be readily cleaned to remove the accumulation of lint and dirt by simply lifting the detector-element and wiping off the yarn-rests.

It has been noted that the present improved device is applicable to other uses than that herein shown and described, and that its form and construction may be varied without departing from the spirit or scope of the invention. Therefore, without limiting ourselves in this respect, we claim:

1. In a device of the type specified, the combination of a standard, a detector-element pivoted on said standard and having a yarn-engaging portion arranged parallel with the pivotal axis of said element and a second yarn-engaging portion disposed at substantially right-angles to its axis, said detector-element being normally movable by the engagement therewith of a slub or other enlargement on the yarn to permit the same to pass through the device, a yarn-rest on the standard having angular faces disposed in parallel spaced relation with respect to the yarn-engaging portions of the detector to provide crossing slits through which the yarn draws, and means to adjust the yarn-rest to alter the width of the slits.

2. In a device of the type specified, the combination of a standard, a detector-element pivoted on said standard and provided with yarn-engaging edges disposed at substantially right-angles to each other in different planes, and adapted to be engaged by a slub or other enlargement on the yarn to move said element, a support on said standard disposed in a plane oblique to the yarn-engaging edges of the detector-element, a yarn-rest slideable on said support and provided with faces arranged at an angle to each other, and means for attaching said yarn-rest to the support with its angular faces adjusted in opposite spaced relation with respect to the yarn-engaging edges on the detector-element to form two slits

through which the yarn draws, the angular faces on the detector-element being adapted to be engaged by an enlargement on the yarn to move said element to open the slits to permit the enlargement to pass therethrough without breaking the yarn.

3. In a yarn-cleaner and slub-detector, the combination of a member having yarn-engaging faces extending at substantially right-angles to each other and arranged one in advance of the other, and a second member having corresponding angular yarn-engaging faces, said second member mounted to move freely with respect to the first member and normally disposed with its angular faces in opposite spaced relation to the corresponding faces of the first member to adapt the yarn to draw through the openings between said faces to clean it on all sides, said movable member being displaceable by the engagement therewith of an enlargement on the yarn to permit the enlargement to pass through the openings without breaking the yarn.

4. In a yarn-cleaner and slub-detector, the combination of a relatively fixed member having yarn-engaging faces disposed at an angle to each other and arranged one in advance of the other, a second member having yarn-engaging faces disposed in opposite spaced relation to the corresponding faces of the fixed member to adapt the yarn to draw therebetween to clean it on all sides, said second member being mounted to move freely with respect to the fixed member when engaged by an enlargement on the yarn to separate the yarn-engaging faces to permit the enlargement to pass through the device without breaking the yarn.

5. In a yarn-cleaner and slub-detector, the combination of a relatively fixed member having yarn-engaging faces extending in planes at an angle to each other, and a member mounted normally free to move with respect to the fixed member and having portions arranged parallel with and spaced away from the yarn-engaging faces thereof to form slits through which the yarn draws to clean it on all sides, said movable member being moved by the engagement therewith of an enlargement on the yarn to open the slits between the yarn-engaging faces whereby the enlargement will pass therethrough without breaking the yarn.

6. A yarn-cleaner and slub-detector comprising a relatively fixed element having yarn-engaging faces extending at right-angles to each other, a second element constructed with angular faces corresponding to those of the fixed element, and means for pivotally mounting said second element with its yarn-engaging faces in opposite spaced relation to those on the fixed element to form two slits extending at right-angles to each other through which the yarn draws, said

5 pivoted element being adapted to be engaged by an enlargement on the yarn to move its yarn-engaging faces away from the corresponding faces on the fixed element to permit the enlargement to pass through the device without breaking the yarn.

7. In a device of the type specified, the combination of a relatively fixed member having two yarn-engaging faces extending at right-angles to each other and arranged 10 one above the other, a second member mounted normally free to move with respect to the first member and having a face arranged parallel with and spaced away from one of the faces of the fixed member and a portion arranged thereabove and having its face spaced away from the other face of the fixed member, the yarn-engaging faces of the second member being adapted to be engaged 15 by an enlargement of the yarn to move said member to carry its faces away from the opposite faces of the fixed member whereby to permit the enlargement to pass through the device without breaking the yarn.

20 8. In a device of the type specified, the combination of a relatively fixed member having yarn-engaging faces arranged one above the other and extending at right-angles to each other, a second member mounted normally free to move with respect to the first member and having faces arranged one 25 above the other in opposite spaced relation to the corresponding faces of the first member to provide a plurality of slits through which 30 the yarn draws, the faces on said movable member being adapted to be engaged by an enlargement on the yarn to cause said member to be moved out of normal position and its faces displaced laterally with respect to 35 those on the fixed member whereby the enlargement is permitted to pass through the device without breaking the yarn.

40 9. In a device of the type specified, the combination of a fixed rest across which the 45 yarn draws, a second rest arranged in advance of and extending at right-angles to the first rest, a normally movable detector-element having two yarn-engaging faces arranged one in advance of the other and disposed in opposite parallel relation with respect to the fixed rests to form two slits 50 through which the yarn draws, the faces on the second member being adapted to be engaged by an enlargement on the yarn to move said member to open the slits to permit the enlargement to pass through the device without breaking the yarn.

55 10. In a device of the type specified, the combination of a relatively fixed member having two yarn-engaging faces arranged one above the other and crossing each other at substantially right-angles, a slub-detector pivoted at one end to adapt it to be tilted with respect to the fixed member and having its 60 free end arranged in parallel spaced relation

with respect to one face of the fixed member and another portion extending in parallel spaced relation with respect to the other face of the fixed member whereby to form two slits through which the yarn draws, the 70 faces on the slub-detector being adapted to be engaged by an enlargement on the yarn to move said detector to open the slits to permit the enlargement to pass through the device without breaking the yarn.

75 11. In a device of the type specified, the combination of a relatively fixed member provided with two yarn-engaging faces extending at substantially right-angles to each other and arranged one in advance of the other, a 80 plate pivotally mounted to adapt it to move with respect to the fixed member and having its free edge arranged in parallel spaced relation to one of the faces of the fixed member, said plate provided with an overhanging portion having its edge arranged in parallel spaced relation to the other face of the fixed member whereby to provide two slits through which the yarn draws to clean it on opposite sides, the pivoted plate being adapted to be 85 engaged by an enlargement on the yarn to swing said plate to displace its yarn-engaging faces away from the corresponding faces on the fixed member whereby to permit the enlargement to pass through the device without 90 breaking the yarn.

95 12. In a device of the type specified, the combination of a relatively fixed member having two yarn-engaging faces disposed at substantially right-angles and arranged one 100 in advance of the other, a second member having two angular faces corresponding to those of the first member, means for pivotally mounting said second member with its angular faces in spaced relation to the corresponding faces of the fixed member to provide crossing slits through which the yarn draws, the faces on the second member providing means for engaging a slub or other enlargement on the yarn on whichever side it 105 may project and such engagement operating to move the pivoted member to open the slits to permit the passage of the enlargement without breaking the yarn, and means for 110 yieldingly maintaining said pivoted member in position with its faces in cooperative relation with those of the fixed member.

115 13. In a device of the type specified, the combination of a member having two yarn-engaging faces extending at substantially right-angles to each other, a second member having two yarn-engaging faces extending at right-angles to each other, means for pivotally mounting the second member with its 120 yarn-engaging faces in parallel spaced relation to the corresponding faces of the first member to provide slits through which the yarn draws, and means for adjusting said members in a plane oblique to their opposed faces to regulate the width of the slits in ac- 125

cordance with the size of the yarn drawing therethrough, the faces on the pivoted member being adapted to be engaged by an enlargement on the yarn to move said member to open the slits to permit the passage of the enlargement therethrough without breaking the yarn.

14. In a device of the type specified, the combination of a relatively fixed member having a projecting arm and a second arm disposed above and crossing the first arm at substantially right-angles thereto, a plate-like detector-element, and means for pivotally mounting said detector-element with one of its edges disposed in parallel spaced relation to the first arm of the fixed member and another edge disposed in parallel relation to the other arm of the fixed member whereby to provide crossing slits through which the yarn draws, the edges of the detector-element being adapted to be engaged by an enlargement on the yarn to swing said element out of cooperative relationship with the fixed member to permit the enlargement to pass through the device without breaking the yarn.

15. In a device of the type specified, the combination of a standard, a detector-element pivoted on said standard to normally move freely with respect thereto and constructed with two yarn-engaging faces extending at substantially right-angles to each other, a thread-rest provided with two angularly disposed faces adapted to cooperate with the yarn-engaging faces of the detector-element to provide slits through which the yarn draws, and means for mounting said thread-rest on the standard to provide for adjusting its angular faces with respect to those on the detector-element to regulate the width of the slits therebetween, said movable detector-element having its edges disposed in position to be engaged by an enlargement on the yarn drawing through the slits to move said element to open the slits to permit the passage of the enlargement without breaking the yarn.

16. In a device of the type specified, the combination of a member having two yarn-engaging faces disposed at substantially right-angles, a second member pivoted to adapt it to move with respect to the first member and having two angular faces arranged parallel and in spaced relation to the angular faces of the first member to form slits through which the yarn draws, the faces on the movable member adapted to be engaged by an enlargement on the yarn to move said member to open the slits to permit the enlargement to pass through the device, and a trip-lever engaging the pivoted member to hold its yarn-engaging faces in cooperative relation to those of the fixed member, said trip-lever being disengageable from the movable member when the latter is moved by the

engagement of an enlargement with one of its faces.

In testimony whereof we hereunto affix our signatures.

WILLIAM MARCROFT. 70
GEORGE N. TAYLOR.
